CRANK OPERATED TOY UTILIZING MARBLES

Raymond C. Gaston, Madeira, Ohio, assignor to The Chas. Wm. Doepeke Manufacturing Company, Inc., Rossmoyne, Ohio, a corporation of Ohio

Application June 13, 1957, Serial No. 46,589

Term of patent 14 years

(Cl. D34—15)

Figure 1 is a perspective view of a crank operated toy utilizing marbles showing new design.

Figure 2 is a side elevational view thereof.

Figure 3 is an end elevational view thereof.

The side of the toy not shown is a substantial mirror image of the side shown in Figure 2.

The marbles are shown in broken lines for illustrative purposes only.

I claim:

The ornamental design for a crank operated toy utilizing marbles, substantially as shown and described.
